UNITED STATES PATENT OFFICE.

CHARLES ALLARDICE, OF COHOES, NEW YORK.

IMPROVEMENT IN KNITTING-MACHINE BURRS.

Specification forming part of Letters Patent No. 42,545, dated May 3, 1864.

To all whom it may concern:

Be it known that I, CHARLES ALLARDICE, of Cohoes, in the county of Albany and State of New York, have invented a new and useful Improvement in Rotary Burrs for Knitting-Machines; and I do hereby declare that the following is a full, clear, and exact description of the same, reference being had to the accompanying drawings, forming a part of this specification, in which—

Figure 1 is a face view of a burr constructed according to my invention. Fig. 2 is a central section of the same. Fig. 3 is a central section of the hub without the bush and sinkers. Fig. 4 is a side view of one of the sinkers.

Similar letters of reference indicate corresponding parts in the several figures.

This invention consists in securing the removable sinkers or wings in oblique radial slots in the hub of the burr by providing a chamber in the bore of the said hub for the reception of dove-tail tongues on the inner edges of the sinkers, and constructing a shoulder on the bush to bear against the said tongues and confine them within the chamber, whereby the construction of the burr is simplified and great facility is afforded for the removal and replacement of the sinkers.

To enable others skilled in the art to construct burrs according to my invention, I will proceed to describe it with reference to the drawings.

A is the hub, made of brass or other metal, of cylindrical form and having oblique radial slots *c* cut in its periphery for the reception of the sinkers or wings B B. The said hub has its central bore smaller on one side, as shown at *a a* in Fig. 3, and larger on the other side, as shown at *b b* in the same figure, the larger bore being somewhat smaller *a* than circle inscribed within the bottom of the slots *c*, provided for the sinkers, and between the larger and smaller bores there is turned in its interior a chamber, *e*, which is sufficiently larger than the bore *b* to meet the slots *c*, and the side of this chamber next the smaller bore, *a*, is beveled, as shown at *i* in Figs. 2 and 3.

The sinkers B have each on its inner edge

a projecting tongue, *n*, which is of such width that it will just enter the chamber *e* when the sinker is inserted into its slot, and of such depth that when the inner edge, *o*, of the sinker is on the bottom of its slot in the hub the edge *r* of the said tongue is within the circle of the bore *b*, that a shoulder, *s*, formed by the larger portion of the bush C, may abut against one side of the said tongue. The edge of the tongue which comes next the bevel *i* of the chamber of the hub is beveled to correspond, giving that side of the tongue a dovetail form.

A portion of the steel bush C is made to fit the larger bore, *b*, of the hub, and another portion to fit the smaller bore, *a*, and a screw-thread is cut on the end of the smaller portion and fitted with a nut, D.

In constructing the burr the sinkers are first placed in the several grooves of the hub with their edges *o* at the bottoms of the said grooves. The bush is then inserted through the bore of the hub from the larger side and the nut applied on the opposite side and screwed up, by which means the shoulder *s* of the bush is made to press against the contiguous edges of the tongues and force their opposite dovetail-edges against the beveled surface *i* of the chamber of the hub, and so secure the sinkers firmly, the dovetail-edges of the tongues preventing them from being drawn out from the hub, while the shoulder on the bush and the face *i* of the chamber confines them in a longitudinal direction.

To take out the sinkers the nut is first taken off and the bush drawn out, and the sinkers can then be drawn from their respective slots in the hub by a pair of pliers.

What I claim as my invention, and desire to secure by Letters Patent, is—

The combination of the chamber *e* in the hub, the dovetail-tongues *n* on the sinkers, and the shoulder *s* on the bush, substantially as and for the purpose herein set forth.

CHARLES ALLARDICE.
